BENDING MACHINE

Paul F. Maize, Detroit, Mich., assignor to Briggs Manufacturing Company, Detroit, Mich., a corporation of Michigan

Application July 10, 1940, Serial 344,760

24 Claims. (Cl. 153—40)

This invention relates to bending machines and more particularly to such machines adapted for bending to desired curvature relatively long pieces of stock.

Bending of relatively long pieces to various shapes, particularly to closed figures, does not present difficulties when such figures approximate a circle or, as it is often expressed in the language of the art, have substantially uniformly changing curvature. With such shapes bending may be easily effected with the aid of a forming plate and a pressure shoe, either of which can be made movable. For instance, a pressure shoe may be made stationary and the plate rotatable, or a pressure shoe may travel around a stationary forming plate forcing a workpiece into a track or groove provided thereon. Great difficulties arise, however, where the desired shapes include relatively sharp corners or turns, and relatively straight portions between them. If it is attempted, for instance, to bend a relatively long workpiece to a substantially rectangular shape, after the pressure shoe passes a corner, the pressure between the shoe and the workpiece is first considerably relieved, but after the pressure shoe reaches a certain point on the straight side of the workpiece (usually the middle thereof) the pressure begins to increase and also to change its direction tending to press on the pressure shoe sideways with an increasing force. In many instances because of the friction involved the pressure shoe soon becomes unable to move in its intended path of travel, since it is pressed transversely with respect to said path, and breakage in the machine becomes inevitable.

It has been attempted to solve the above difficulty by providing means which in addition to rotating the forming plate also move it bodily along various paths. However, structures embodying such solutions are very complicated and expensive to build. In addition, each machine is constructed for one shape only and cannot be used for other shapes. In many cases a machine of the above character requires an investment of several thousand dollars and yet it can be used for bending a workpiece to a single form or shape.

One of the objects of the present invention is to provide an improved bending machine for bending relatively long workpieces such, for instance, as window frame moldings for motor vehicles, to desired shapes.

Another object of the invention is to provide an improved bending machine which can be used for producing various bent shapes with only slight

replacements in the operative parts of the machine.

A further object of the invention is to provide a bending machine in which there are provided improved means for actuating the form plate and the pressure-shoe along an improved path, whereby very complicated movements of the form plate and mechanisms producing such movements in conventional machines are largely eliminated.

10 A still further object of the invention is to provide an improved bending machine having a rotatable plate and a pressure shoe adapted to be maintained in an operative contact with the workpiece and actuated with respect to said plate in such a manner that only rotation of the plate is necessary for bending workpieces to various curvatures and yet no excessive side pressures on the shoe occur at any time during the operation cycle.

20 A still further object of the invention is to provide an improved bending machine for bending relatively long pieces to shapes having relatively sharp turns or corners, without producing objectionably high unit pressures between the pressure shoe and the workpiece.

It is an added object of the present invention to provide a bending machine of the foregoing character, which is simple in construction, dependable in operation and relatively inexpensive to manufacture.

Other objects and advantages of this invention will appear in the following description and appended claims, reference being had to the accompanying drawings forming a part of this specification wherein like reference characters designate corresponding parts in the several views.

Fig. 1 is a front view of the bending machine embodying the present invention, the machine being shown ready to begin its operation cycle.

40 Fig. 2 is an end view of the machine of Fig. 1, the observer being presumed to look on the right-hand side thereof.

Fig. 3 is a fragmentary sectional view taken in the direction of the arrows on the section plane passing through the section line 3—3 of Fig. 1.

45 Fig. 4 shows a workpiece as it is removed from the machine after the completion of the bending operation.

50 Fig. 5 is an enlarged transverse sectional view of the workpiece, said view being taken in the direction of the arrows on the section plane passing through the line 5—5 of Fig. 4.

Fig. 6 is a diagrammatic view illustrating the hydraulic circuit operating the pressure shoe

actuating means, and the electric circuit controlling said hydraulic circuit, the parts of the machine being shown in positions for bending movement (to the right) of the pressure shoe.

Fig. 7 is a view similar in part to Fig. 6 but showing the parts of the machine in positions for idle movement (to the left) of the pressure shoe.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings there is shown, by way of example, a bending machine embodying the present invention. The machine is shown and hereinafter described as adapted for bending a window or garnish molding for a motor vehicle. It will be understood, however, that the machine is applicable for bending workpieces of other descriptions and having different types of curvatures than those herein illustrated and described.

Referring to the drawings and particularly to Fig. 1 thereof, the machine illustrated therein comprises a base 10 on which there is rotatably mounted a forming plate 11 of a shape substantially corresponding to that of the finished workpiece. The forming plate 11 is provided with a peripheral track or groove 11a (see Fig. 3) adapted to receive a workpiece 12 as the same is forced into said track for bending. Means are provided for locking one end of the workpiece 12 to the forming plate 11, said means being exemplified in the present embodiment of the invention by a hinged bracket 13 brought into locking position by a handle 14 as illustrated in Fig. 3. As can be clearly seen in said Fig. 3, pushing the handle 14 away from the plate causes the bracket 13 to press on the workpiece 12, thus holding the same securely to the forming plate 11. Pushing the handle 14 toward the forming plate 11 unlocks the bracket 13 and the workpiece 12.

The forming plate 11 is secured to a shaft 15 journaled in the base 10 and driven from the motor 16 through a speed reducing device 17. In the machine illustrated in Fig. 1 the forming plate rotates in a counterclockwise direction.

It is an important feature of the present invention that while the forming plate 11 is adapted to rotate around the fixed axis of the shaft 15, a pressure shoe 18 cooperating with the track 11a of the forming plate is movable not only toward and away from the forming plate 11, as is common with conventional structures, but is also movable intermittently along the forming track 11a. In the present embodiment of the invention such movements of the pressure shoe 18 are effected with the aid of active means adapted to produce active forces and to move said pressure shoe simultaneously in two substantially perpendicular directions.

In the present embodiment of the invention said means are exemplified by a head frame 20 slidable in guideways formed on guide blocks 21 provided on the base 10. The head frame 20 is actuated with the aid of two opposing cylinders 22 and 23 mounted on the base 10. Said cylinders are provided respectively with fluid

actuated pistons 24 and 25 connected to said head frame 20 with the aid of piston rods 26 and 27, respectively. It will be understood that as the fluid pressure in cylinders 22 and 23 varies 5 the head frame 20 will slide along the guideways 21. It is preferable to use liquid for actuating the pistons 24 and 25 in order to attain quick starting and stopping of said pistons.

The head frame 20 carries a head 30 slidable 10 in guideways 31, provided in the head frame 20, in a direction substantially perpendicular to that of the guideways 21. The head 30 carries the pressure shoe 18 which shoe is connected to said head to receive bending pressure therefrom. The 15 pressure shoe 18 is adapted to rock on the head 30 within predetermined limits. Return of the pressure shoe 18 to its normal position is ensured with the aid of two springs 32.

Means actuating the head 30 are exemplified 20 in the present embodiment of the invention by a cylinder 33 provided with a fluid actuated piston slidably fitted therein and connected to said head 30 by means of a piston rod 35. The cylinder 33 is provided with conduits 36 and 37. By admitting liquid under pressure through one of said 25 conduits, using the other as an exhaust conduit, it is possible to move the head 30 and, consequently, the pressure shoe 18 toward and away from the forming plate 11 as desired or to cause 30 the pressure shoe 18 to remain in pressure contact with the forming plate 11 irrespective of whether said plate 11 is stationary or rotates around its axis. Conduits 36 and 37 may be provided with proper control valves or plugs (not 35 shown) which may be either manually or automatically operated.

From an examination of the drawings, and particularly of Fig. 1 thereof, it will be understood that since the plate 11 is not of the circular 40 form, should the pressure shoe 18 be in contact with said plate while the same rotates, the pressure shoe will move along a path parallel to the axis of the piston rod 35. With forming plates substantially conforming to a circular shape and 45 having very small variations in the rate of change of the curvature thereof, which is to say, having no relatively sharp turns, bending of a workpiece may be effected by merely holding the pressure shoe against the plate as the same rotates, or 50 moving the pressure shoe along the forming track or groove if the forming plate is stationary. However, when, as in the present instance, the forming plate is of such a shape that bending has to be done around relatively sharp turns or 55 corners, the unit pressures between the pressure shoe and the workpiece in places along the forming track may assume directions transverse to the direction of pressure exerted on the pressure shoe, and in some cases may become perpendicular thereto. Under such conditions bending of the workpiece becomes extremely difficult and 60 a breakage in the pressure shoe actuating means may result. Even if a machine is constructed strong enough to withstand such objectionable 65 forces, the unit pressures between the pressure shoe and the workpiece change so greatly during a single operation cycle that the surfaces of the bent workpiece come out uneven and rough.

In accordance with the present invention 70 means are provided with the aid of which the pressure shoe 18 is moved along the forming track by means separate from those exerting bending pressure on the shoe 18. In the present embodiment of the invention said means are exemplified by the above described hydraulic

means including cylinders 22 and 23 with pistons adapted to move the head frame 20 and, consequently, the pressure shoe 18 in opposite direction and substantially perpendicular to the axis of the piston rod 35. Thus, in effect, the pressure shoe 18 is capable of moving in any direction in the plane of rotation of the forming plate 11 and remain at the same time in pressure contact with the workpiece.

The hydraulic circuit controlling the movements of the head frame 20 is illustrated diagrammatically in Figs. 6 and 7. As shown in said figures, it comprises a source of fluid pressure 40 connected by means of a conduit 41 with control cylinders 42 and 43 in which cylinders there are slidably fitted suitable valves, in the present instance recessed pistons 44 and 45. By means of compression coil springs 46 and 47, the pistons 44 and 45 are held in their upright positions unless some external means, such as solenoids 48 and 49 in the present instance, bring them down against the opposition of the respective springs. When either of the recessed pistons is in its down position it connects the source 40 with a respective head frame actuating cylinder.

In the position of operative parts illustrated in Fig. 6, the fluid pressure from the source 40 is transmitted through the conduit 41 to the control cylinder 43 and therefrom through the conduits 50a and 50b to the left-hand portions of the cylinders 22 and 23. Under such conditions pistons 24 and 25 move to the right, thereby moving the head frame 20 and, consequently, the head 20 and the pressure shoe 18 carried thereby, to the right. If under such conditions there is sufficient fluid pressure in the upper portion of the cylinder 33 to exert pressure on the shoe 18, said shoe will move to the right along the forming plate track, remaining at the same time in contact with the workpiece 12. The above described condition is one that takes place at the beginning of the operation cycle. It will be understood that the commencing operation cycle presumes inserting the workpiece 12 into the forming track and locking one end thereof in said track as previously described and as illustrated in Fig. 3, admitting fluid pressure through the conduit 36 into the cylinder 33 and setting the plate 11 to rotation. Means are provided whereby said operations may be performed either simultaneously or successively. However, such means are well known in the art and, therefore, detailed description thereof is not deemed necessary in the present instance.

The down position of the recessed piston 45 as well as the upward position of the recessed piston 44 is ensured under the described condition by energizing the solenoid 49 and deenergizing the solenoid 48. Said solenoids are electrically connected to a suitable source of electric energy 50 and are controlled by a spring loaded two-way switch generally indicated by the numeral 51, said switch being carried by the pressure shoe 18. In its normal position the switch 51 is closed by means of the spring 52 thereby connecting the solenoid 49 with the source 50, and at the same time disconnecting the solenoid 48 from said source. The energized solenoid 49 overcomes the resistance of the spring 47 and brings the recessed piston 45 down while the deenergizing solenoid 48 is not capable of opposing the spring 46 which moves the recessed piston 44 upward disconnecting the conduit 53 from the source 40, but connecting said conduit 53 with an exhaust port 54.

Thus, as soon as the machine is started the pressure shoe 18 moves to the right along the straight portion 56 of the forming track provided on the plate 11. Since no bending takes place in such a movement the same is relatively rapid. At the end of said movement a finger 51a contacts a pin 57 on the forming plate, in consequence whereof the switch 51 is operated to break the circuit energizing the solenoid 49 and to close the circuit energizing the solenoid 48. Such a condition is illustrated in Fig. 7. When such operation of the switch occurs and the solenoid 48 is energized, the recessed piston 44 moves down against the resistance of the spring 46 providing a connection between the source 40 through the conduits 41, 53 and 53a with the right-hand portions of the head frame actuating cylinders 22 and 23. Deenergizing of the solenoid 49 occurring under such conditions permits the spring 47 to move the piston 45 upward interrupting the connection between the source 40 and left-hand portions of the cylinders 22 and 23 and establishing a connection between said left-hand portions of cylinders 22 and 23 with the exhaust port 55 provided in the cylinder 43. It will be clearly understood from an examination of Fig. 7 that under such conditions the pistons 24 and 25 and, consequently, the head frame 20 will move to the left.

It should be understood that under the conditions described above rotation of the plate 11 in the counterclockwise direction continues and, therefore, for a definite length of time the pressure shoe 18 and the pin 57 move to the left with very little relative movement. However, a certain amount of movement of the pressure shoe 18 over the rounded corner adjacent the pin 57 takes place. As the pressure shoe 18 moves over the rounded corner 56a, bending the workpiece in such movement and proceeds to move toward the side 58, it is brought well to the left-hand side of the shaft 15. In moving away from the pin 57, the finger 51a of the switch loses contact with the pin, thereby changing the electric circuits. Then the spring 52 of the switch becomes effective to close the same and to bring it into the position shown in Fig. 6, thus energizing the solenoid 49 and causing the operative parts of the machine to be set for movement of the head frame 20 to the right.

Movement of the pressure shoe 18 to the right along the side 58 of the forming plate 11 proceeds similarly to the above described movement thereof along the side 56. When the pin 59 on the forming plate is reached, the same being at that moment above and to the right of shaft 15, the finger 51 engages said pin 59 and, therefore, the pressure shoe 18 moves to the left as the pin 59 revolves bodily around the axis of the shaft 15. As the pin 59 continues its rotation, the finger 51a of the switch loses contact with the pin 59 and the switch is operated to cause movement of the pressure shoe 18 to the right along the side 60 of the plate 11. This movement is relatively rapid and the shoe reaches a pin 61 when the same is at the upper right-hand side of the shaft 15. The finger 51a again comes in contact with a pin, this time the pin 61a on the forming plate, and operates the switch permitting the pressure shoe 18 to move to the left as the said pin 61 revolves around the shaft axis 15. At the end of the leftward movement of the pressure shoe 18, the contact between the finger 51a and the pin 61 ceases, in consequence whereof the pressure shoe 18 is moved to the right along the side 62

of the plate 11, reaching the end of the forming track and completing the bending operation. Means are provided whereby the rotation of the forming plate 11 ceases at this moment and the pressure shoe 18 is withdrawn from its contact position with the forming plate 11. The workpiece 12 is then removed from the forming track and the working cycle is thus completed. A new piece is inserted onto the track and one end thereof is locked as described above whereupon the operation cycle may begin anew.

It should be noted that in view of the fact that sides 60 and 62 of the forming plate 11 are relatively short the pins 59 and 61 are flattened as is shown in Fig. 6 in order to produce snapping action in the switch at those points and thus to accelerate its operation.

It will now be clear in view of the foregoing that the above described bending machine may be used for bending workpieces to various curvatures without reconstructing the machine. In order to adapt the machine for a different job it is only necessary to change the forming plate and to provide contact pins at the corners thereof. The operation of the pressure shoe 18 will remain substantially the same, and the machine may be successfully used as explained above despite the fact that the workpiece is bent to an entirely different curvature.

I claim:

1. In a bending machine, a forming plate having a track adapted to receive a workpiece and rotatable around a fixed axis, means for rotating said plate, a pressure shoe, pressure means adapted in operation to urge yieldingly said shoe toward said plate, and fluid actuated means adapted to move said shoe at predetermined times during the operation cycle along the track of said forming plate to bend the workpiece.

2. In a bending machine, a forming plate having a peripheral track adapted to receive a workpiece, said plate being rotatable around a fixed axis, means for rotating said forming plate, a pressure shoe adapted to contact the workpiece on said track and to exert bending pressure thereon, and hydraulically actuated means adapted to move said shoe along said track in two directions during a single operation cycle.

3. In a bending machine, a forming plate having a peripheral track adapted to receive a workpiece, said plate being rotatable around a fixed axis, driving means for rotating said forming plate, a pressure shoe adapted to contact the workpiece on said track and to exert bending pressure thereon, and two opposing cylinders with two hydraulically actuated pistons slidably fitted in said cylinders, respectively, and connected to said pressure shoe to move the same along said track in two directions during a single operation cycle.

4. In a bending machine, a forming plate rotatable around a fixed axis, said plate being provided with a peripheral groove adapted to receive a workpiece, means drivingly connected to said plate for rotating the same, a pressure shoe adapted to contact the workpiece in said groove and to exert bending pressure thereon, a cylinder with a fluid actuated piston operatively arranged therein and connected to said pressure shoe to exert pressure thereon and to move it toward and away from said forming plate, two opposing cylinders each having a fluid actuated piston connected to said pressure shoe for moving the same in opposite directions along said groove during a single revolution of said plate.

5. In a bending machine, a forming plate rotatable around a fixed axis, means drivingly connected to said plate for rotating the same, said plate being provided with a peripheral groove adapted to receive a workpiece, a pressure shoe adapted to contact the workpiece in said groove and to exert bending pressure thereon, a cylinder with a fluid actuated piston operatively arranged therein and connected to said pressure shoe to exert pressure thereon and to move it toward and away from said forming plate, two opposing cylinders each having a fluid actuated piston connected to said pressure shoe for moving the same during a single operation cycle in opposite directions along said groove and in the plane of rotation of said plate.

6. In a bending machine, a forming member having a track adapted to receive a workpiece, said member being rotatable around a fixed axis, means for rotating said forming member, a pressure shoe adapted to contact the workpiece on said track and to exert bending pressure thereon, hydraulically actuated means adapted to move said shoe along said track, and electric means controlled by said forming member in its rotation and adapted to control said hydraulically actuated means.

7. In a bending machine, a forming member rotatable around a fixed axis, means for rotating said forming member, said member being provided with an external track adapted to receive a workpiece, a pressure shoe adapted to contact the workpiece on said track and to exert bending pressure thereon, a cylinder with a fluid actuated piston operatively arranged therein and connected to said pressure shoe to exert pressure thereon and to move it toward and away from said forming member, a cylinder having a fluid actuated piston connected to said pressure shoe from moving the same in opposite directions along said track during a single revolution of said plate, and electric means controlled by said forming member in its rotation and adapted to control the operative pressure in said last-named cylinder.

8. In a bending machine, a forming plate rotatable around a fixed axis, means drivingly connected to said plate for rotating the same, said plate being provided with a peripheral track adapted to receive a workpiece, a pressure shoe adapted to contact the workpiece in said track and to exert bending pressure thereon, a cylinder with a fluid actuated piston operatively arranged therein and connected to said pressure shoe to exert pressure thereon and to move it toward and away from said forming plate, a cylinder having a fluid actuated piston connected to said pressure shoe for moving the same in opposite directions along said track during a single revolution of said plate, electrically actuated means adapted to control fluid pressure in said last named cylinder, and an electric switch controlled by said plate in its rotation, said switch being, in turn, adapted to control said electrically actuated means.

9. In a bending machine, a forming plate rotatable around a fixed axis, means drivingly connected to said plate for rotating the same, said plate being provided with a groove adapted to receive a workpiece, means for locking one end of said workpiece in said groove, a pressure shoe adapted to contact the workpiece in said groove and to follow said groove for bending said workpiece, a head adapted to carry said pressure shoe, a pressure cylinder having a fluid actuated piston connected to said head and adapted to exert pressure thereon and to move said head and said shoe

toward and away from said groove, and two opposing cylinders each having a fluid actuated piston connected to said head for moving said pressure shoe along said groove as said plate rotates.

10. In a bending machine, a forming plate rotatable around a fixed axis, motor means drivingly connected to said plate for rotating the same, said plate being provided with a groove adapted to receive a workpiece, means for locking one end of said workpiece in said groove, a pressure shoe adapted to contact the workpiece in said groove and to follow said groove for bending said workpiece, a head adapted to carry said pressure shoe, a pressure cylinder having a fluid actuated piston connected to said head and adapted to exert pressure thereon and to move said head and said shoe toward and away from said groove, and two opposing cylinders each having a fluid actuated piston connected to said head for moving said pressure shoe along said groove intermittently during the single operation cycle as said plate rotates.

11. In a bending machine, a forming plate rotatable around a fixed axis, means drivingly connected to said plate for rotating the same in one predetermined direction, said plate being provided with a track adapted to receive a workpiece, means for locking one end of said workpiece on said track, a head movable in the plane of rotation of said plate along two substantially perpendicular paths, and a pressure shoe carried by said head and adapted to contact the workpiece on said track and to follow said track for bending said workpiece.

12. In a bending machine, a forming plate rotatable around a fixed axis, means for rotating said plate in one predetermined direction, said plate being provided with a groove adapted to receive a workpiece, means for locking one end of said workpiece in said groove, two opposing cylinders each having a fluid actuated piston slidably therein, a head frame actuated by said pistons and movable in the plane of said forming plate, a head carried by said head frame and movable therein transversely of the path of said head frame, and a pressure shoe carried by said head and adapted to contact the workpiece in said groove and to follow said groove for bending said workpiece.

13. In a bending machine, a base, a forming plate rotatable around an axis fixed with respect to said base and provided with a peripheral track adapted to receive a workpiece as the same is forced thereinto for bending, means for rotating said plate in one predetermined direction, means locking one end of said workpiece to said track, two opposing cylinders mounted on said base each having a slidably fitted hydraulically actuated piston, a head frame, said pistons being operatively connected to said frame for moving the same substantially in the plane of rotation of said plate, a head carried by said frame and movable therein transversely of the line of travel of said head frame, fluid actuated means carried by said head frame and adapted to move said head toward and away from said forming plate, and a pressure shoe carried by said head and adapted to contact the workpiece in said track and to follow the same for bending said workpiece.

14. In a bending machine, a base, a forming plate mounted on said base for rotation around a fixed axis and provided with a forming track adapted to receive a workpiece as the same is forced thereinto for bending, means for rotating said forming plate in one predetermined direction, means locking one end of said workpiece

to said track, guideways provided on said base adjacent said forming plate, a head frame slidably in said guideways, two opposing cylinders mounted on said base each having a hydraulically actuated piston slidably fitted therein and connected to said head frame for moving the same in said guideways, a head carried by said frame and movable therein substantially perpendicular to said guideways, means adapted to press at predetermined times said head toward said forming plate, and a pressure shoe carried by said head and adapted to contact the workpiece in said track and to exert bending pressure thereon as said forming plate rotates.

15. In a bending machine, a forming plate rotatable around a fixed axis, said plate being provided with a peripheral track adapted to receive a workpiece, means for rotating said plate, a pressure shoe adapted to contact the workpiece in said track and to exert bending pressure thereon, yielding means connected to said pressure shoe and adapted to exert pressure thereon and to move it toward and away from said forming plate, a cylinder having a fluid actuated piston slidably fitted therein and connected to said pressure shoe to move the same transversely of the path in which it is moved by said yielding means, a valve controlling fluid pressure in said cylinder, a solenoid mechanically connected to said valve to actuate the same, a switch operated by said forming plate and electrically connected to said solenoid to control the same to cause at predetermined portions of the operation cycle movements of said pressure shoe along said peripheral track.

16. In a bending machine, a forming plate rotatable around a fixed axis, said plate being provided with a peripheral track adapted to receive a workpiece, means for rotating said plate, a pressure shoe adapted to contact the workpiece in said track and to exert bending pressure thereon, yielding means connected to said pressure shoe and adapted to exert pressure thereon and to move it toward and away from said forming plate, a cylinder having a fluid actuated piston slidably fitted therein and connected to said pressure shoe to move the same transversely of the path in which it is moved by said yielding means, a valve controlling fluid pressure in said cylinder, a solenoid connected to said valve to actuate the same, a switch carried by said pressure shoe and electrically connected to said solenoid to control the same, and means provided on said forming plate and adapted to operate said switch as said plate rotates.

17. In a bending machine, a forming plate rotatable around a fixed axis, said plate being provided with a peripheral track adapted to receive a workpiece, means for rotating said plate, a pressure shoe adapted to contact the workpiece in said track and to exert bending pressure thereon, yielding means connected to said pressure shoe and adapted to exert pressure thereon and to move it toward and away from said forming plate, a cylinder having a fluid actuated piston slidably fitted therein and connected to said pressure shoe to move the same transversely of the path in which it is moved by said yielding means, a valve controlling fluid pressure in said cylinder, a solenoid mechanically connected to said valve to actuate the same, a switch carried by said pressure shoe and electrically connected to said solenoid to control the same, and a pin on said plate adapted to contact said switch and to operate the same when said shoe reaches a predetermined point along said track.

18. In a bending machine, a rotatable forming plate having a track adapted to receive a work-piece, means for rotating said plate around a fixed axis, a pressure shoe, means for maintaining said pressure shoe in pressure contact with said workpiece and to move said shoe along a straight line path toward and away from said plate, and means for producing active forces and connected to said shoe for moving the same transversely of said straight line path and along said track.

19. In a bending machine, a rotatable forming plate having a track adapted to receive a work-piece, means for rotating said plate around a fixed axis, a pressure shoe, pressure exerting means adapted to maintain said pressure shoe in pressure contact with said workpiece and to move said shoe along a straight line path toward and away from said plate, and fluid actuated means adapted to move said shoe and said pressure exerting means bodily along a path substantially perpendicular to said straight line path and along said track.

20. In a bending machine, a forming member having a curved peripheral track with changing rate of curvature and adapted to receive a work-piece to be bent, said member being rotatable around a fixed axis, means for rotating said forming member, a pressure shoe, means for maintaining said pressure shoe in pressure contact with said workpiece, and reciprocating means for exerting on said shoe a force capable of moving said shoe in either of two directions along the workpiece independently of rotation of said forming member.

21. In a bending machine, a forming member having a curved peripheral track with changing rate of curvature and adapted to receive a work-piece to be bent, said member being rotatable

around a fixed axis, means for rotating said forming member, a pressure shoe, means for maintaining said pressure shoe in pressure contact with said workpiece, and means for exerting on said shoe a force capable of moving said shoe along said track independently of rotation of said forming member.

22. In a bending machine, a forming member having a curved peripheral track with changing rate of curvature and adapted to receive a work-piece to be bent, said member being rotatable around a fixed axis, means for rotating said forming member, a pressure shoe, means for maintaining said pressure shoe in pressure contact with said workpiece, and fluid actuated means for exerting on said shoe at predetermined times forces capable of moving said shoe along said workpiece independently of rotation of said forming member.

23. A bending machine according to claim 21 in which said last-named means comprises a slide connected to the shoe and opposed cylinders having fluid actuated pistons connected to said slide.

24. In a bending machine a forming member having a curved peripheral track with changing rate of curvature and adapted to receive a work-piece to be bent, said member being rotatable around a fixed axis, means for rotating said forming member, a pressure shoe, means for maintaining said pressure shoe in pressure contact with said workpiece, and means for exerting on said shoe a force capable of moving said shoe along the workpiece in a direction opposite to the direction of rotation of said workpiece and independently of the rotation of the forming member.

PAUL F. MAIZE.
